(57) **CLAIM**

The ornamental design for a soap holding pouch, as shown and described.

DESCRIPTION

FIG. 1 is a front elevation view of a soap holding pouch showing my new design;

FIG. 2 is a rear elevation view thereof;

FIG. 3 is a right side elevation view thereof;

FIG. 4 is a left side elevation view thereof;

FIG. 5 is a top plan view thereof;

FIG. 6 is a bottom plan view thereof;

FIG. 7 is an isometric view thereof; and,

FIG. 8 is an in use view thereof showing the attachability of a suction cup to a shower wall.

The dashed lines within the boundaries of the claimed invention are stitching and form part of the claimed design. The dash-dot-dot lines in FIG. 8 depict environmental subject matter only and form no part of the claimed design.
